BY Frederick W. Hyatt
ATTORNEY

UNITED STATES PATENT OFFICE.

FRED G. LIADY, OF CISCO, TEXAS, ASSIGNOR OF ONE-HALF TO ALICE DOUBLE, OF LOS ANGELES, CALIFORNIA.

WIRE-LINE CUTTER.

Application filed October 5, 1920. Serial No. 414,766.

To all whom it may concern:

Be it known that I, FRED G. LIADY, a citizen of the United States, residing at Cisco, in the county of Eastland and State of Texas, have invented a new and useful Wire-Line Cutter, of which the following is a specification.

My invention relates to means for cutting wire lines employed in the boring of artesian and oil wells.

An object of the invention is to provide an impact wire line cutter in which the wire cutting operation is effected during the downward stroke of the device and by reason of its impact against an object to which the wire line is connected.

Another object of my invention is to provide a device of the character referred to which may be readily and simply operated and which will function positively and accurately.

A further object of my invention is to provide such a device which will be simple and economical in construction.

Other objects and advantages will appear from the subjoined detailed description wherein I have set forth a preferred form of device embodying my invention.

In the accompanying drawings:

Figure 1 illustrates a side elevation of a device embodying my invention.

Fig. 2 illustrates a side elevation of the same taken at right angle to Fig. 1.

Fig. 3 illustrates a horizontal section taken on a line indicated by x^3-x^3 , in Fig. 1.

Fig. 4 illustrates a fragmentary vertical section taken on a line indicated by x^4-x^4 , in Fig. 3.

Fig. 5 illustrates a horizontal section taken on a line indicated by x^5-x^5 , in Fig. 1.

Fig. 6 illustrates a vertical section taken on a line indicated by x^6-x^6 , in Fig. 3.

Fig. 7 illustrates a vertical section of the same corresponding to Fig. 6 but with the device in line cutting position.

Referring to the drawings, 1 indicates a body provided with a stem 2. The stem 2 may be of any desired form or shape. The body 1 is formed with a central bore or slideway 3. A line receiving passage or slot 4 communicates with the bore 3. The bore or slideway 3 of the body 1 terminates in an inner tapered wall 5.

A cylindrical carrier or block 6 is shift-

ably mounted within the bore 3. The carrier 6 is provided with a central bore 7 and a line receiving passage or slot 8 registering with the line receiving passage 4. A plate 9 is affixed to the body 1 by suitable means 60 10. The plate 9 carries a lug or stop 11 which projects within the slot 12 formed on the periphery of the carrier 6. Preferably a fillet 13 is borne by the plate 9 and is interposed within the line receiving passage 4. 65 A cutter or knife 14 is pivotally supported at its upper end by a pin 15 within the line receiving passage 8 of the carrier 6. An opposed cutter or knife 16 is pivoted at its upper end within a slot 17 formed in the carrier 6. The cutters 14 and 16 are provided with line cutting edges 18 and with riders 19 adapted to engage the taper 5.

In operation, the device is put in use by applying the body 1 to the line at the top of 75 the well so that the line illustrated at a extends through the central bore 3. The carrier 6 with the cutter 16 positioned therein is applied to the line a below the body 1. The cutter 14 is then positioned within the 80 carrier 6 by inserting the pin 15. The carrier is then inserted within the central bore 3 by either lifting the carrier 6 relative to the body 1 or lowering the latter onto the carrier. The plate 9 is then affixed to the 85 body 1 with the lug 11 projecting within the slot 12 of the carrier.

In operation, the carrier 6 will be maintained within the bore 3 in the relative position illustrated in Fig. 6 by the lug 11 engaging the top of the slot 12 of the carrier. 90 In this position the device is lowered within the well. Upon striking the line socket illustrated as b in Fig. 7, the carrier 6 will be forcibly moved relatively upward within 95 the bore 3, thereby actuating the cutters 14 and 16 through contact with the taper 5. The cam action of the taper 5 will force the cutting edges 18 of the cutters 14 and 16 together severing the line a .

My invention is not limited to the particular embodiment illustrated in the drawings and described in the specification, wherein I have set forth preferred details of construction and proportion.

I claim:

1. An impact wire line cutter having a body provided with a bore and terminating in an outwardly tapered inner wall, a carrier mounted within said body and shiftable 100

- longitudinally thereof, opposed cutters pivoted to said carrier and engaging said tapered wall to sever a line when said carrier forcibly engages the line socket.
5. 2. A wire line cutter comprising a body having a central bore and a stem, the body terminating in a tapered inner wall and formed with a wire receiving passage communicating with the central bore, a plate ¹⁰ fixed to the body and closing the wire receiving passage, a cylindrical carrier slidably mounted in the bore, the carrier having a central bore and a wire receiving passage, means carried by the plate and engaging the carrier to maintain the carrier within the bore, and opposed cutters pivoted to the carrier and operable by engagement with the tapered inner wall to sever a line upon lengthwise movement of the carrier upward ¹⁵ within the body.
15. 3. A wire line cutter comprising a body having a central bore and a stem, the body terminating in a tapered inner wall and formed with a wire receiving passage communicating with the central bore, a plate ²⁰ fixed to the body and closing the wire receiving passage, a cylindrical carrier slidably mounted in the bore, the carrier having a central bore and a wire receiving passage, means carried by the plate and engaging the carrier to maintain the carrier within the bore, and opposed cutters pivoted to the carrier and operable by engagement with the tapered inner wall to sever a line upon lengthwise movement of the carrier upward within the body.

3. An impact line cutter having a body providing a slideway which terminates in an outwardly tapered wall, a carrier loosely shiftable on the slideway, and a cutter pivoted on the carrier and adapted to sever a line when shifted along said tapered wall.

4. An impact line cutter having a body providing a slideway terminating in an outwardly tapered portion, a carrier loosely mounted on the slideway, a lug limiting the downward sliding movement of said carrier, and a cutter pivoted to the carrier and adapted to sever a line when moved over said tapered slideway.

Signed at Los Angeles, California, this 35
24th day of September, 1920.

FRED G. LIADY.
